APPARATUS FOR AGITATING MATERIALS

William Ashley Kline, Morris Plains, John Alexander Monick, Teaneck, and Elio Eliakim Tarika, East Orange, N. J., assignors to Colgate-Palmolive-Peet Company, Jersey City, N. J., a corporation of Delaware

Application July 21, 1951, Serial No. 237,946

2 Claims. (Cl. 259—96)

1

The present invention relates to apparatus for agitating materials and has particular reference to apparatus for effectively mixing, blending, processing, etc., materials such as heavy chemical solutions, solids suspended in heavy liquid vehicles, viscous compounds, and the like. The apparatus is adapted for mixing, blending, kneading, shearing, etc. such materials to rapidly disintegrate and uniformly distribute any solids through a vehicle or homogeneously mix fluids of varied specific gravity or viscosity.

In accordance with the present invention there is provided a novel apparatus for mixing materials which comprises a suitable chamber, preferably of cylindrical shape, adapted to hold a mass of materials. Where required or desired said chamber may be of sufficient strength to withstand high pressure and it may be provided with means to heat or cool it externally. A rotatable shaft is axially mounted within said chamber upon which a plurality of impellers are mounted. Means are provided within and near one end of said chamber adapted to cooperate with one of said impellers to effectively shear the materials being agitated.

The apparatus imparts turbulent motion to portions of the mass of materials being agitated and also causes the mass to flow in certain fairly well recognizable paths, including a generally circulatory motion of the mass which produces a vortex adjacent to the shaft, a generally downward motion adjacent to the shaft, and a generally upward motion adjacent to the wall of the chamber which takes materials from the top of the mass downwardly and brings materials from the body of the mass upwardly. The upward and downward motion of a particular portion of the mass is probably interrupted or modified as it moves into the path of an impeller, which assures thorough mixing and blending of materials in the mass.

In order to indicate even more fully the advantages and capabilities of the present invention, reference is made to the following description, taken in conjunction with the accompanying drawing which by way of illustration shows a preferred embodiment of the novel apparatus. It will be understood that other embodiments of the invention employing the same or equivalent principles may be used and that structural

2

changes may be made as desired without departing from the present invention and the purview of the appended claims. In the drawing similar reference characters are used to designate corresponding parts in each of the several figures.

In the drawing:

Fig. 1 is a view in vertical sectional elevation of an apparatus in accordance with a preferred embodiment of the present invention; and

Fig. 2 is a sectional view of the apparatus as taken along line 2—2 of Fig. 1, looking in the direction of the arrows.

Referring first to Fig. 1 of the drawing, the apparatus comprises a generally cylindrical chamber 8 having a cylindrical side wall 10, a domed bottom wall 12 and a cover plate 14, the latter being provided with one or more material inlet openings 16 (one shown), a sight glass 18 and a manhole 20. Chamber 8 is provided, with, 15 a jacket 22 having an inlet 24 and an outlet 26 for heating or cooling fluid. Bottom wall 12 is provided with a suitable material outlet opening, e. g., flush valve 28. A thermo well 30 is located at any convenient position in side wall 10.

25 A rotatable shaft 32 comprising a rotatable longitudinally extending interior member 34 and a rotatable exteriorly surrounding sleeve member 36, the latter being of somewhat shorter extension and adapted to rotate at a speed different from the former, passes axially through chamber 8. Interior member 34 is journaled in bottom wall 12 of said chamber in a suitable bearing 38 adapted to bear the thrust of the shaft. Sleeve member 36 is journaled in a bearing 40, 30 which is axially mounted within cover plate 14 and which is adapted to bear the thrust of said sleeve member. Both bearings 38 and 40 are constructed so as to resist leakage of liquids under operating pressures. Member 34 is provided with a longitudinally extending key 44, the function of which will be described more fully hereinafter.

Members 34 and 36 of shaft 32 may be driven in any suitable manner. For example, in the 45 preferred embodiment of the invention, interior member 34 is driven through spur gears 46 by a motor 48 mounted on a bracket 50 secured to chamber 8. Exterior member 36 is driven through bevel gears 52 by a motor 54 mounted on a bracket 56 secured to chamber 8. As shown on the draw-

ing and in the preferred embodiment of the present invention, spur gears 46 are enclosed in a gear reduction box 57 mounted on bracket 50 secured to chamber 8 while bevel gears 52 are enclosed within a gear box 58 mounted on a bracket 59 secured to chamber 8.

A stator 60 is mounted within chamber 8 near the domed bottom wall 12 thereof by a plurality of brackets 62 secured to side wall 12 of said chamber. As shown more clearly in Fig. 2 stator 60 comprises an annular member 64 provided with a plurality of vertically projecting baffle members or vanes 66.

An impeller 68 is positioned within the opening defined by annular member 64 and vanes 66 of stator 60 and is mounted on interior member 34 of shaft 32 for rotation therewith. Said impeller is provided with an integrally formed collar 70 having a locking member, e. g., a set screw 72, adapted to engage key 44 on interior member 34 to prevent longitudinal movement of the impeller along said member. Impeller 68 is further provided with a plurality of generally radially extending blades 74 which are preferably of sufficient length whereby the same may rotate freely within the opening defined by vanes 66 of stator 60 with only slight clearance to effect a shearing action of the materials being agitated. As indicated on the drawing, blades 74 preferably are curved in a direction opposite to their direction of rotation. If desired, however, said blades may be substantially non-curved or straight.

A second impeller 76 is mounted on interior member 34 of shaft 32 for rotation therewith at any convenient position above impeller 68. Impeller 76 is provided with an integrally formed collar 78 having a locking member, e. g., a set screw 80, adapted to engage key 44 on member 34 to prevent longitudinal movement of the impeller along said member. Key 44 is further adapted to cooperate with slots or grooves (not shown) in impellers 68 and 76 to inhibit relative rotative movement of the same upon member 34.

Impeller 76 is further provided with a plurality of generally radially extending blades 81 which may be disposed in a plane parallel to that of wall 10 of chamber 8 or in any plane not greater than about 45° from the plane defined by said wall. A third impeller 82, similar in structure to impeller 76, is secured to the end of sleeve member 36 of shaft 32.

In using the novel apparatus herein described the materials which are to be mixed, blended, processed, etc., are introduced into chamber 8 through material inlet openings 16 located in cover plate 14. Motors 48 and 54 then are started to cause members 34 and 36 of shaft 32 and impellers 68, 76 and 82 to rotate.

A portion of the mass of materials being agitated by impeller 68 is caught between the baffles 66 of stator 60 and the ends of blades 74 of the impeller where the same is subjected to a shearing action whereby contiguous parts of the mass are caused to slide relative to one another to become mixed. Another portion of the mass is thrown against baffles 66 with an impact force sufficient to effectively break up any large lumps of materials into relatively small particles.

The mixing is continued until a completely homogeneous mass has been produced, that is, until all of the solid materials, for example, have been disintegrated and uniformly distributed throughout the mass. Thereafter, a uniform mix-

ture may be withdrawn conveniently through flush valve 28.

As indicated hereinbefore, the novel apparatus of the present invention is capable of widespread application in mixing, blending, processing, etc., various materials possessing similar or different physical characteristics. The apparatus herein described may be used extensively for forming homogeneous intimate blends or mixtures of any of the various kinds and types of materials used in the detergent, textile, cosmetic, dye, plastic, leather, etc., industries. In the detergent industry alone, for example, the apparatus may be used to thoroughly mix soap and/or synthetic detergent slurries during as well as after formulation, to obtain adequate mixing of viscous soap and/or detergent slurries; to allow for the incorporation of powdered solids into slurries without lump formation due to hydration; etc.

While there has been described what is considered at present to be the preferred embodiment of the invention, it will be understood, of course, that many modifications and changes and substitutions may be made therein without departing from the true scope of the invention as defined in the appended claims.

Having thus described the invention what is claimed is:

1. An apparatus for agitating materials comprising in combination, a chamber adapted to contain a mass of material, said chamber having a generally cylindrical side wall and a bottom wall, a longitudinally extending shaft movably mounted within said chamber, said shaft having an interior member and an exteriorly surrounding sleeve member, the sleeve member being of shorter extension than the interior member, means for rotating the sleeve member in the same direction as and at a slower speed than said interior member, at least one impeller mounted on each of said members, said impellers being spaced apart a substantial distance and having a plurality of blades extending outwardly from said shaft, each impeller being adapted to permit the materials being agitated to pass through the chamber between the blades of each impeller, and means mounted near the bottom wall of said chamber adjacent to one of said impellers adapted to cooperate with the rotating blades of said adjacent impeller to shear the materials being agitated, said means comprising an annular member and a plurality of vertically projecting, radially extending baffle members, said annular member being secured to the upper edges of said baffle members and being of a width sufficient to cover only said baffle members, leaving the blades of said adjacent impeller uncovered.

2. An apparatus for mixing materials comprising in combination, a chamber adapted to contain a mass of material, said chamber having a generally cylindrical side wall and a domed bottom wall, a pair of concentric mixer shafts axially mounted within said chamber, the inner shaft being of longer extension than the outer shaft, means for rotating said shafts in the same direction at different speeds, at least one impeller mounted on each of said shafts, said impellers being spaced apart a substantial distance and being provided with a plurality of blades extending radially outwardly from said shaft, each impeller being adapted to permit the materials being agitated to pass through the chamber between the blades of each impeller, and an annular disc mounted near the domed bottom wall of said chamber adjacent to one of said impellers,

5

said disc having a plurality of vertically projecting, radially extending baffle members secured to its lower surface and being of a width sufficient to cover only said baffle members, leaving the blades of said adjacent impeller uncovered.
